[57] CLAIM

The ornamental design for a terminal output printer or the like, substantially as shown and described.

DESCRIPTION

FIG. 1 is a perspective view taken from the right front of a terminal output printer or the like showing my new design;

FIG. 2 is a perspective view taken from the right rear of the terminal output printer shown in FIG. 1.

FIG. 3 is a front elevational view of the terminal output printer shown in FIG. 1 on an enlarged scale.

FIG. 4 is a right-hand side elevational view of a terminal output printer as shown in FIG. 1 on an enlarged scale.

FIG. 5 is a top plan view of a terminal output printer as shown in FIG. 1 on an enlarged scale.
